HAT BRIM STRETCHING MECHANISM

Rudolph G. Muller, Irvington, N. J.

Application April 8, 1938, Serial No. 200,866

13 Claims.

(Cl. 223—15)

This invention relates to improvements in hat making machinery, and the invention has reference, more particularly, to improvements in that type of hat body stretching mechanism known to the industry as brim stretchers.

In brim stretching machines as heretofore constructed, the mechanism for oscillating or vibrating the stretcher members has generally been located overhead, i. e. above the hat bat or body supporting means. Such overhead arrangement of the means for operating the stretcher members not only adds considerably to the complication thereof, especially with respect to means for moving the same into and out of service position, but also involves risk of the dropping of dirt, oil or other foreign matter therefrom onto the hat bat undergoing treatment.

It is an object of this invention to provide a novel construction of brim stretching mechanism wherein the stretcher members and the means for adjusting and actuating the same are substantially located below the level of the hat bat or body supporting means in such manner as to render the latter more easily accessible for deposit and removal of the work, while at the same time eliminating risk of soiling the work through the dropping of dirt, oil or other foreign matter thereon.

The invention has for another object to provide a novel hat brim stretching apparatus having novel means for adjusting the work supporting means, and novel means for adjusting and actuating the stretcher members per se, including means for regulating at will the effective amplitude of operative oscillation of said stretcher members.

The invention has for a further object to generally improve and simplify the means by which the operator controls and directs the functioning of the brim stretcher mechanism during operation thereof.

Other objects of this invention, not at this time more particularly enumerated, will be understood from the following detailed description of the same.

An illustrative embodiment of this invention is shown in the accompanying drawings, in which:

Fig. 1 is a plan view of the hat brim stretching machine according to this invention, with the stretcher members retracted to out of service position; Fig. 2 is a longitudinal vertical section through the machine, taken on line 2—2 in Fig. 1; Fig. 3 is a transverse vertical section through the machine, taken on line 3—3 in Fig. 2; and

Fig. 4 is a horizontal sectional view, taken on line 4—4 in Fig. 2.

Fig. 5 is a view similar to that shown in Fig. 2; but with the stretcher members advanced to service position.

Similar characters of reference are employed in the above described views, to indicate corresponding parts.

Referring to the drawings, the reference character 10 indicates the bed-plate of the machine, the same being supported by legs 11. Suitably affixed to said bed-plate 10, in upstanding relation thereto, is a central standard or column 12, having an axial bore 13. Extending upwardly through the bore 13 of said standard or column 12 is a vertically adjustable carrier rod 14, upon the upper exteriorly projecting end of which is a suitably shaped hat bat supporting block 15.

Affixed to the upper end portion of said standard or column 12 is a fixed hub plate 16. Slidably mounted on said standard or column 12, below said fixed hub plate 16 is a movable hub plate 17. Pivottally connected with the periphery of said fixed hub plate 16 are a plurality of circumferentially spaced dependent radially extendible brim spreader members 18. Pivottally interconnected between said brim spreader members 18 and the marginal portions of said movable hub plate 17 are links 19.

Supported from said bed-plate 10 by upstanding posts 20 is a stationary frame ring 21, which is disposed concentric to but somewhat below the hat bat supporting block 15 and its brim spreader members 18. Affixed to said frame ring 21, in circumferentially spaced relation about the same, are fulcrum bearings 22. Pivottally supported by said fulcrum bearings 22 are carrier brackets 23.

These carrier brackets are each formed to provide an outwardly off set, upwardly extending bifurcated or forked carrier member 24, and an inwardly off set, downwardly extending tail member 25. Slidably mounted on said standard or column 12, below said movable hub plate 17 is a second movable hub plate 26. Pivottally interconnected between the marginal portions of said second movable hub plate 26 and the lower free end portions of said respective tail members 25 are links 27.

Pivottally connected with the upper end portions of said carrier members 24 are dependent brim stretcher members 28. Said brim stretcher members are provided with outwardly projecting actuator arms 29. The free end portions of said actuator arms 29 are preferably interconnected with the free end portions of corresponding brim stretcher members 28 by integral bracing mem-

bers 30, thus providing a rigid oscillatable structure.

Disposed exteriorly of and concentric to said frame ring 21 is a vertically reciprocable actuator ring 31. Pivotaly interconnected between said actuator ring 31 and the free end portions of said brim stretcher member actuator arms 29 are links 32.

As shown more especially by Fig. 1 the relative relation of said brim stretcher members 28 and said brim spreader members 18 is such that the former are opposed to the latter in alternated or staggered relation, whereby said brim stretcher members 28 operate between pairs of adjacent brim spreader members 18.

The means for inducing vertical reciprocatory movement of said actuator ring 31, for producing, at proper times, operative oscillation of said brim stretcher members 28 relative to the stationary brim spreader members 18, comprises the following drive mechanism:

Affixed to and projecting rearwardly from the bed-plate 10 are transversely spaced bracket members 33 upon which are suitably secured bearing members 34. Journaled in and between said bearing members 34 is a transverse drive shaft 35, which is provided at its respective ends with eccentric crank studs 36 (see Fig. 2). Fixed on said drive shaft 35 is a balance or fly wheel 37. Also fixed on said drive shaft 35 is a belt pulley 38 for driving the same from any suitable source of power. It will be understood, however, that said drive shaft may be driven by any other desired type of power transmission means. Suitably affixed to said bed-plate 10, in upstanding relation thereto, are a pair of laterally spaced bearing pedestals 39; the same being located between the actuator ring 31 and the rearward end of said bed-plate 10. Journaled in and between said bearing pedestals 39 is a transverse fulcrum or rock shaft 40. Fullcrumed by said rock shaft 40 are rocking bars or levers 41, the forward ends of which are pivotally connected by trunnions 42 respectively with the sides of said actuator ring 31. Extending between the rearward ends of said rocking bars or levers 41 is a transverse regulator shaft 43 having eccentric trunnions 44 with which said rearward ends of said rocking bars or levers 41 are pivotally engaged. Interconnected between the eccentric crank studs 36 of said drive shaft 35 and the main portion of said regulator shaft 43 are connecting rods 45. Said regulator shaft 43 is provided with a squared wrench receiving portion 46, or other suitable tool engageable means, for application of a tool thereto for rotatively adjusting said regulator shaft for purposes hereinafter explained. Suitably mounted on the rearwardly extending portions of said rocking bars or levers 41 are weights 47 for counterbalancing said actuator ring 31. In order to prevent rotative displacement or tipping of said actuator ring 31 from normal horizontal plane, especially when the latter is vertically reciprocated bodily to actuate the brim stretcher members 28, steady bars 48 are affixed to the sides of said actuator ring 31 to depend therefrom. Pivotaly interconnected between the lower free ends of said steady bars 48 and anchoring pivots 49, connected with certain bed-plate supporting legs 11, are check links 50.

Foot treadle actuated mechanism is provided for both bringing the brim spreader members and brim stretcher members into and out of service position, as well as for controlling the

degree of stretching pressure applied by said stretcher members while operating. This mechanism comprises a frame member 51 which is affixed to and dependent from the under side of said bed-plate 10 in transverse disposition and centrally aligned relative to the standard or column 12. Said frame member 51 includes side members 52, which terminate at their lower ends in bearing portions 53. Extending between said side members 52, above said bearing portions 53, is a bridge portion 54. Mounted on said bridge portion 54 is a guide bearing member 55 having a pair of inner guide bearings 56, and a pair of outer guide bearings 57. Affixed by their upper ends to said movable hub plate 17, to extend downwardly therefrom and slidably through the movable hub plate 26, bed-plate 10, frame member base 51 and through the inner guide bearings 56 and underlying bridge portion 54, are a pair of perpendicular brim spreader control rods 58. Adjustably fixed on said control rods 58 are stop collars 59 the position of which determines the normal initial starting position of said movable hub plate 17, and consequently the desired degree of extended projection of the brim spreader members 18 to service position. Affixed by their upper ends to said second movable hub plate 26, to extend downwardly therefrom and slidably through the bed-plate 10, frame member base 51 and through the outer guide bearings 57 and underlying bridge portion 54, are a pair of perpendicular brim stretcher control rods 60.

Journaled in and between the bearing portions 53 of said frame member 51 is a pivoting shaft 61 to operatively support a pair of rocker levers 62 having forwardly extending arms 63 and rearwardly extending arms 64. Affixed to the underside of said bed-plate 10, in suitable locations to depend therefrom in laterally spaced apart relation, are hanger bearings 65. Journaled in and between said hanger bearings 65 is a fulcrum shaft 66 for pivoting the rearward ends of forwardly extending treadle frame bars 67 which straddle the frame member 51 and associated mechanism. The forward end portions of said treadle frame bars 67 extend outwardly beyond the forward end of said bed-plate 10, and attached to and supported by and across said forward end portions of the treadle frame bars 67 is a treadle plate 68. The treadle frame bars 67 are respectively interconnected by links 69 with the forward free ends of the arms 63 of said rocker levers 62. Suitably affixed to the rearwardly extending arms 64 of said rocker levers 62 are weights 70 to counterbalance the latter to normal initial position and the treadle means connected therewith to normal initial raised position.

Pivotaly mounted on said pivoting shaft 61, between the rocker levers 62, is a rearwardly extending elevator lever 71. Affixed upon the free end portion of said elevator lever 71 is a knuckle member 72 to which is pivotally connected the lower end of thrust link 73, the transverse pivoting pin of which provides laterally and oppositely extending lift studs 74 which respectively overhang the path of upward swinging movement of the rearward arms 64 of said rocker lever 62, so as to be engageable by the latter at proper times. Affixed to the brim spreader control rods 58 is a yoke member 75 to which the upper end of said thrust link 73 is pivotally connected.

Affixed respectively to the brim stretcher control rods 60 are coupler members 76. Pivotaly interconnected between these coupler members 76

76 and the forwardly extending arms 63 of said rocker levers 62 are links 77.

Means is provided for adjusting and regulating the height of the hat bat supporting block 5 15, to accommodate the same to given crown height sizes of the hat bats. This means comprises a pivoted footing member 78 with which the lower end of the carrier rod 14 is engaged. Affixed to and dependent from the bed-plate 10 10 is a screw threaded stud 79 which extends downwardly through an opening 80 provided in said footing member 78. Threaded on said stud 79 so as to engage supportingly the underside of said footing member 78 is an adjusting hand-wheel 81. By turning said hand-wheel 81 up or down on said stud 79, the footing member 78 may be correspondingly swung up or down to, in turn, lift or lower said carrier rod 14 for raising or lowering said hat bat supporting block 15. 20

In the use of the machine, after the hat bat supporting block 15 is adjusted to a height adapted to accommodate it to the particular hat bat to be worked upon, said hat bat is pulled down over and upon said supporting block with 25 the brim portions thereof overlying the retracted brim spreader members 18. Power being applied to the drive shaft 35, rotation of the crank studs 36 thereof transmits, through the connecting rods 45, vertical oscillatory movement to the rocking bars 41, which, in turn, produces a vertical or up and down bodily movement of the actuator ring 31. This movement of the actuator ring 31 is transmitted, through the links 32, to the actuator arms 29 of the brim stretcher members 28, thereby oscillating the same about their pivotal connections with the carrier members 24, so as to effect an in and out movement of said stretcher members.

The brim stretcher members being in motion, 40 the operator thereupon applies his foot to the treadle plate 68 to move the same downward, thus swinging down the treadle frame bars 67. The down swinging movement of said treadle frame bars 67 is transmitted through the links 45 69 to the rocker levers 62, thereby causing a downward swinging movement of their forwardly extending arms 63 and an upward swinging movement of their rearwardly extending arms 64. As the arms 64 rise they engage the lift studs 74 so as to produce an upward movement of the elevator lever 71 and the thrust link 73 connected therewith. The upward movement of the thrust link 73 is transmitted, through the yoke connection 75, to the brim spreader control rods 58, 55 causing the latter to rise and slide upwardly on the column or standard 12 the upper movable hub-plate 17. The upward movement of the hub-plate 17 is transmitted through the links 19 to the brim spreader members 18, which are thereby 60 swung upwardly and outwardly to lift the brim section of the hat bat so as to hold the same subject to operative engagement by the oscillating brim stretcher members 28.

Simultaneously with the movement of the brim spreader members 18 to service positions as described, the downward swinging arms 63 of the rocker levers 62 is transmitted, through the links 71, to the brim stretcher control rods 60, causing the latter to descend and slide downwardly on the column or standard 12 the lower movable hub plate 26. The downward movement of the hub plate 26 is transmitted through the links 27 to the tail members 25 of the pivoted carrier brackets 23, and is translated into an outward swinging 70 movement of the latter which produces an in-

ward swinging movement of the carrier members 24 of said carrier brackets. This inward movement of said carrier members 24 carries the oscillating brim stretcher members 28 inwardly and into operative engagement with the brim section 5 of the hat bat where spread over and supported by the outswung brim spreader members 18. The oscillating contact of the brim stretcher members stretches the felt between adjacent brim spreader members in a manner familiar to those skilled in 10 the hat making art.

It will be obvious that the operator by varying the downward pressure of his foot on the treadle may increase or decrease the stretching contact pressure exerted by the oscillated brim stretcher members 28, and consequently by his skilled sense of feeling and by his skilled observation of the work can gradually effect the stretching out of the brim sections of the hat bat as desired. Owing to the fact that the actuating and control 20 mechanisms are all substantially below the plane of the hat bat, the observation of the progress of the work is greatly facilitated, while risk of the dropping of oil, dirt or other foreign matter from working parts of the mechanism onto the hat bat, 25 to the detriment of the latter, is entirely eliminated.

The degree of maximum extension of the brim spreader members 18 may be regulated by pre-determining the initial position of the hub-plate 30 17 by vertical adjustment of the latter. This is accomplished by adjusting the stop collars 59 on the control rods 58.

The effective limit of stretching stroke of the stretcher members 28 may be adjustably controlled by rotatively adjusting the regulator shaft 35 43 which rotates the eccentric trunnions 44 to move the rocking bars 41 independently of the drive shaft crank studs 36, to thereby raise or lower the initial position of the actuator ring 31 40 thus retracting or advancing the initial positions of the stretcher member 28 relative to the hat bat supporting means.

From the above it will be understood that the mechanism is very flexibly and easily adjustable 45 to establish desired operative selected positions of the hat bat supporting means, as well as desired initial spaced relation of the stretching means relative to said supporting means.

In operation a very easy control of the operating mechanism is attainable by the operator merely by varying the pressure of the foot upon the treadle means, thus providing a control method which is physically less tiring than hand control; use of the hands being required only for depositing and removing the work from the machine. 55

As many changes could be made in the above described constructions, and many apparently widely different embodiments of this invention 60 could be made without departing from the scope thereof, as defined by the following claims, it is intended that all matter contained in the above description or shown in the accompanying drawings shall be interpreted as illustrative and not in 65 a limiting sense.

I claim:

1. In a machine of the kind described, a work support including radially extendible brim spreader members, a frame ring concentric to and 70 fixed in a horizontal plane below said work support and its brim spreader members, oscillatable brim stretcher members spaced around said work support in opposed staggered relation to said spreader members, carrier brackets pivotally 75

mounted on said frame ring to support said stretcher members subject to movement into and out of cooperative working relation to said spreader members, a vertically reciprocable actuator ring concentric and adjacent to said frame ring, said actuator ring having means operatively connecting the same with said stretcher members, power operated means for vertically reciprocating said actuator ring, and foot treadle control means for simultaneously moving said spreader and stretcher members into cooperative working relation.

2. In a machine of the kind described as defined in claim 1, wherein said means for reciprocating the actuator ring comprises, rocking bars by and between the forward ends of which said actuator ring is carried, a drive shaft having crank means, and connecting rods interconnecting said crank means and the rearward ends of said rocking bars.

3. In a machine of the kind described as defined in claim 1, wherein said means for reciprocating the actuator ring comprises, pivoted rocking bars by and between the forward ends of which said actuator ring is carried, a drive shaft having crank means, a rotatively adjustable regulator shaft extending between the rearward ends of said rocking bars and having eccentric pivotal connections with the latter, and connecting rods interconnecting said drive shaft crank means with said regulator shaft.

4. In a machine of the kind described as defined in claim 1, wherein said means for reciprocating the actuator ring comprises, pivoted rocking bars by and between the forward ends of which said actuator ring is carried, counter-balancing weights on the rearward end portions of said rocking bars, a drive shaft having crank means, and connecting rods interconnecting said crank means with the rearward ends of said rocking bars.

5. In a machine of the kind described as defined in claim 1, wherein said means for reciprocating the actuator ring comprises, pivotally mounted rocking bars by and between the forward ends of which said actuator ring is carried, a drive shaft having crank means, connecting rods interconnecting said crank means with the rearward ends of said rocking bars, steady bar means affixed to and dependent from said actuator ring, and pivotally anchored check link means pivotally engaged with said steady bar means.

6. In a machine of the kind described, a supported bed-plate, an upstanding tubular column on said bed-plate, a carrier means extending through said column, a hat bat receiving block supported by the upper end of said carrier means, a fixed hub-plate on the upper end of said column, radially extendible brim spreader members pivotally connected with said fixed hub-plate, a movable hub-plate vertically slidable on said column, links pivotally interconnected between said movable hub-plate and said spreader members, a stationary ring supported from said hub-plate in concentric relation to said column, carrier brackets pivotally mounted on said stationary ring, oscillatable brim stretched members fulcrumed on said carrier brackets and spaced around said block in opposed staggered relation to said spreader members, a second movable hub-plate vertically slidable on said column, links pivotally interconnected between said second movable hub-plate and said carrier brackets, foot treadle control means below said bed-plate, and

control rod means interconnecting the respective movable hub-plates with said foot treadle control means, whereby operation of the latter simultaneously moves said hub-plates to bring said spreader and stretcher members into cooperative working relation.

7. In a machine of the kind described as defined in claim 6, means for oscillating the stretcher members comprising, a vertically reciprocable actuator ring exteriorly concentric to said stationary ring, links pivotally interconnected between said actuator ring and said stretcher members, and power operated means for reciprocating said actuator ring.

8. In a machine of the kind described as defined in claim 6, means for oscillating the stretcher members comprising, a vertically reciprocable actuator ring exteriorly concentric to said stationary ring, links pivotally interconnected between said actuator ring and said stretcher members, pivotally mounted rocking bars by and between the forward ends of which said actuator ring is carried, a drive shaft having crank means, and connecting rods interconnecting said crank means with the rearward ends of said rocking bars.

9. In a machine of the kind described as defined in claim 6, means for oscillating the stretcher members comprising, a vertically reciprocable actuator ring exteriorly concentric to said stationary ring, links pivotally interconnected between said actuator ring and said stretcher members, pivotally mounted rocking bars by and between the forward ends of which said actuator ring is carried, a drive shaft having crank means, connecting rods interconnecting said crank means with the rearward ends of said rocking bars, steady bar means affixed to and dependent from said actuator ring, and pivotally anchored check link means pivotally engaged with said steady bars.

10. In a machine of the kind described, a central upstanding column having a work support associated with its upper end, a fixed hub-plate on said column below said work support, radially extendible brim spreader means pivotally connected with said hub-plate, a movable hub-plate vertically slidable on said column, links pivotally interconnected between said movable hub-plate and said spreader members, oscillatable brim stretcher members spaced around said work support in opposed staggered relation to said spreader members, pivotally mounted carrier brackets by which said stretcher members are supported subject to movement into and out of cooperative working relation to said spreader members, a second movable hub-plate vertically slidable on said column, links pivotally interconnected between said second movable hub-plate and said carrier brackets, foot treadle control means, and means connected between said respective movable hub-plates and said foot treadle control means, whereby operation of the latter simultaneously moves said hub-plates to bring said spreader and stretcher members into cooperative working relation.

11. In a machine of the kind described, a central upstanding column having a work support associated with its upper end, a fixed hub-plate on said column below said work support, radially extendible brim spreader means pivotally connected with said hub-plate, a movable hub-plate vertically slidable on said column, links pivotally interconnected between said movable hub-plate and said spreader members, oscillat-

able brim stretcher members spaced around said work support in opposed staggered relation to said spreader members, pivoted carrier brackets by which said stretcher members are supported subject to movement into and out of cooperative working relation to said spreader members, a second movable hub-plate vertically slidable on said column, links pivotally interconnected between said second movable hub-plate and said carrier brackets, pivoted rocker lever means, a pivoted foot treadle means, means operatively interconnecting said foot treadle means and said rocker lever means, vertically movable control rod means for each movable hub-plate, means actuated by the upswinging portion of said rocker lever means for operating the control rod means of said first mentioned movable hub-plate, and means actuated by the downswinging portion of

said rocker lever means for operating said second movable hub-plate, said operations serving to bring said spreader and stretcher members into cooperative working relation.

12. In a machine of the kind described as defined in claim 11, means for oscillating the stretcher members comprising, a vertically reciprocable actuator ring, links pivotally interconnected between said actuator ring and said stretcher members, and power operated means 5 for reciprocating said actuator ring.

13. In a machine of the kind described as defined in claim 11, means for adjustably determining the normal initial position of said first mentioned movable hub-plate thereby to predetermine the limit of operative radial extension of said spreader members. 15

RUDOLPH G. MULLER.
